UNITED STATES PATENT OFFICE.

CHARLES A. FASSEN, OF ST. LOUIS, MISSOURI, ASSIGNOR OF ONE-HALF TO THOMAS I. HART, OF ST. LOUIS, MISSOURI.

MARKING-TAG.

1,166,119.

Specification of Letters Patent. Patented Dec. 28, 1915.

Application filed July 22, 1915. Serial No. 41,281.

To all whom it may concern:

Be it known that I, CHARLES A. FASSEN, a citizen of the United States, residing at the city of St. Louis, State of Missouri, have 5 invented a certain new and useful Improvement in Marking-Tags, of which the following is a full, clear, and exact description, such as will enable others skilled in the art to which it appertains to make and use the 10 same, reference being had to the accompanying drawings, forming part of this specification.

This invention relates to marking tags adapted for attachment to merchandise for 15 the purpose of affording means upon which prices or other markings may be placed.

The purposes of this invention are to provide a form of tag which may be economically manufactured, which may be quickly 20 and easily attached to the merchandise, and which, when attached, will not be subject to inadvertent displacement; which is of such form as to obviate the possibility of its catching on the material or other articles 25 with which it is brought in contact, and which affords a convenient and specially adapted means upon which markings may be placed.

Other objects will be obvious or hereinafter pointed out.

In the drawings, Figure 1 is a perspective view showing my invention as attached to a necktie. Fig. 2 is a plan view of the tag in unfolded position. Fig. 3 is a back view 35 of the tag in folded position. Fig. 4 is a back view in secured position, and Fig. 5 is a section taken substantially on line 5—5 of Fig. 4.

As is readily apparent from the illustrations, it will be seen that my improved tag may be blanked out of any suitable flexible sheet material in the form of a strip 1 which is divided by fold lines 2 into three sections, viz,—an intermediate section 4, a 45 tongue section 5, and a slot section 6. The tongue section and the slot section are slightly shorter than the intermediate section 4. The tongue section is formed with diagonally converging edges which terminate at a locking tongue 7, having locking shoulders 8 extending beyond the adjacent diagonal edges. Adjacent the locking tongue 7, a retaining aperture 9 is formed in the tongue section, the same being of any desired 55 and suitable outline.

The slot section 6 is provided with a slot 10 extending transversely of the section, and of irregular form such as to leave a retaining tongue 11 which is directed transversely of the slot and longitudinally of the 60 section 6. This retaining tongue 11 is of suitable contour to enter the retaining slot 9 of the tongue section, and is disposed upon the same axis perpendicularly to the fold lines 2, as is the retaining aperture 9. The 65 locking slot 10 and the locking tongue 7 are likewise disposed on the same axis perpendicularly to the fold lines 2.

As will be seen in Fig. 3, the distance between the free end of the retaining tongue 70 11 and the adjacent fold line 2 is slightly greater than the width between the terminal edge of retaining slot 9 and the side of the locking tongue 7. As also shown in Fig. 3, it will be seen that the length of the locking tongue 7 exceeds the length of slot 10, the length of slot 10 being a trifle more than the length of locking tongue 7 less the length of one of the shoulders 8.

The tag is attached to an article of merchandise by folding the same thereabout, bending it on the fold lines 2. The locking tongue 7 is then inserted in slot 10 over retaining tongue 11, which may be done by inserting first one end of the locking tongue 80 and moving it laterally until the adjacent diagonal edge of tongue section 5 contacts with the material at the end of slot 10, which will give sufficient clearance between the other end of locking tongue 7 and the other 85 end of slot 10 to permit the complete insertion of the locking tongue therethrough. When so inserted, locking tongue 7 will of course lie below slot section 6 and consequently below the free extremity of retaining tongue 11 which will occupy the space afforded by retaining slot 9. The outer corners of locking tongue 7 may be beveled or rounded off as in the manner shown to facilitate the insertion of the tongue through 90 the slot 10. When thus placed in position, it will be observed that tongue section 5 is interlocked with slot section 6, both by virtue of the fact that the length of tongue 7 exceeds the length of slot 10, and by virtue 95 of the fact that retaining tongue 11 extends through retaining slot 9. When so placed in position, the tag is not subject to inadvertent removal except by such extraordinary force as is sufficient to tear the tag. Fur- 100 105 110

thermore, the tag presents a smooth exterior, free from projections which would be likely to engage material with which it is brought in contact. The outer surface of the tag being plain, it is adapted for the reception of markings.

It is obvious that this tag is very economical to manufacture, as it may be formed entirely in a single blanking operation from 10 an integral sheet of material.

I am aware that the device is capable of various obvious modifications not herein illustrated or described without departing from the scope of the invention involved.

15 What I claim is:

1. A marking tag made of a sheet of flexible material divided by fold lines into a plurality of sections foldable upon one another, one of said sections being formed with a locking slot and an engaging tongue extending thereto, and another of said sections being formed with a terminal locking tongue insertible within said locking slot when the sections are in folded position and a slot adjacent to said locking tongue adapted to permit the passage of the retaining tongue therethrough.

2. A marking tag made of a sheet of flexible material divided by fold lines into a plurality of sections foldable upon one another, one of said sections being provided with a transversely extending locking slot, a terminal one of said sections being formed with a terminal locking tongue disposed on the axis 35 of the slot, said tongue being formed with locking shoulders and inclusive thereof exceeding the length of said locking slot, said locking tongue, exclusive of one of said locking shoulders being less than the length of 40 said locking slot, for the purpose described.

3. A marking tag made of a sheet of flexible material divided by fold lines into a plurality of sections foldable one upon another, one of said sections being formed with a slot 45 therethrough, and a retaining tongue adjacent to said slot, the terminal one of said

sections being formed with an end portion insertible through said slot and an aperture adjacent thereto adapted to permit the passage of said retaining tongue whereby to retain the end portion against withdrawal from the slot.

4. A marking tag formed of sheet material and divided by fold lines into an intermediate section and two terminal sections, 50 one of said terminal sections being provided with a slot therethrough, and a retaining tongue adjacent said slot, the other of said terminal locking sections being formed with a terminal tongue insertible through said 55 slot and adapted to engage walls thereof to lock the terminal sections together and an aperture adjacent said terminal tongue adapted to permit the passage of said retaining tongue into engagement with the terminal tongue whereby to hold it against withdrawal from the slot.

5. A marking tag made of a flexible strip divided into a plurality of sections by fold lines, which sections are foldable upon one 70 another, one of said sections being provided with a slot therethrough, a terminal one of said sections having an extremity formed for insertion through said slot, said slotted section and said terminal section being 75 provided with engaging portions apart from said slot and extremity adapted to prevent withdrawal of said extremity from said slot.

6. A marking tag comprising a flexible strip provided with a slot therethrough, and 80 a retaining tongue projecting into said slot, one extremity of said strip being formed for locking engagement in said slot, and provided with an aperture adapted to permit the passage of said tongue therethrough.

In testimony whereof I hereunto affix my signature in the presence of two witnesses, this 20th day of July, 1915.

CHAS. A. FASSEN.
